UNITED STATES PATENT OFFICE.

JOHN C. WOBERMIN, OF BRUSH, COLORADO.

SANITARY EXPANSIBLE ROOST.

Application filed December 20, 1927. Serial No. 241,366.

This invention relates to hen houses, and particularly to the roosts therefor.

The general object of the invention is to provide an expandible support for a plurality of roosts, the support being so constructed that it may be collapsed or contracted within the hen house during the day to thus leave ample room for the movement of the chickens around the hen house and may 10 project out at night so as to provide roosts disposed at intervals throughout the depth of the hen house.

A further object is to provide a sanitary roost.

15 Other objects will appear in the course of the following description.

My invention is illustrated in the accompanying drawing, wherein:—

Figure 1 is a sectional view of a chicken 20 house constructed in accordance with my invention and showing my improved chicken roost expanded;

Figure 2 is a top plan view of the chicken roost expanded;

25 Figure 3 is a sectional view through one of the perches;

Figure 4 is a fragmentary vertical section through the apron, roller and brush of the roost shown in Figure 1;

30 Figure 5 is a side elevation of a modified form of roost and apron, the pan, the floor and the wall being shown in section;

Figure 6 is a fragmentary front elevation of one of the perches, showing the 35 means for attaching it to the lazy-tongs;

In the drawing, I have illustrated a hen 40 house of conventional or ordinary form. Disposed within the hen house are a plurality of supporting members 10 which may be located adjacent one wall of the hen house, and attached to this wall in any suitable manner and attached to this member 10 is the vertically extending bar 11. Mounted upon this bar are a plurality of clips 12.

45 One of these clips may be permanently or rigidly fastened to the bar and the other clips being slidably mounted thereon. This bar and the supporting member 10 may extend nearly the full height of the hen house or to any desired elevation, but in the drawing the bar is supposed to be about five and a half feet high and the lowermost wall of the hen house will be about seven feet high. The hen house is shown as provided with a concrete floor 13.

50 Pivotaly attached to the clips are the

bars 14 of a lazy-tongs. These bars 14 are disposed in two series, the bars of one series extending at right angles to the bars of the other series and pivoted to each other at 60 15 in the usual and well known manner. Each of the upwardly and forwardly extending bars at its upper end carries the transversely extending perches or roosts 16. Each of these roosts, as shown in Figure 3, is 65 longitudinally grooved, as at 17, and disposed in this groove is a strip of felt which is kept soaked in kerosene for the purpose of keeping off lice.

As illustrated, each of the upwardly and forwardly extending bars 14, which bars are made of metal, are formed so as to provide a forwardly extending flange 18 upon which the perch 17 is disposed. Each perch is supported by as many lazy-tongs as may be 70 found necessary as, for instance, two located at the ends of the perch, and preferably the lazy-tongs are of such size and may be expanded to such position that when expanded the lazy-tongs will extend from 75 the rear wall to the front wall of the hen house with the perches disposed about a foot apart. By making the arms 14 which support the three lowest perches shorter than the other arms and making the last three 80 arms longer than the other arms, it is possible to provide for a greater number of perches and at the same time provide for contracting the lazy-tongs into a smaller compass than would be possible if the arms 85 of the lazy-tongs were all of the same length or extended upward to the same height. In order to support the middle portion of the lazy-tongs, one or more recesses 19 are provided, these being pivoted to one of the pivots of the lazy-tongs, as at 20, in such position that it will rest upon the floor when the lazy-tongs is either contracted or expanded.

Under some circumstances it is desirable 100 that means be provided to catch the droppings from the roosts, and to this end I have provided a pan and a flexible apron which will be drawn out as the roost is expanded and which will contract as the roost is contracted, and provide means whereby any droppings caught upon this canvas may be discharged into the pan. As illustrated in Figure 1, I provide a pan 21 mounted in 105 any suitable manner at the rear of the chicken coop as, for instance, upon the rear wall or upon the vertical members 10, this pan

having a width, of course, equal to the distance between the lazy-tongs. If there are a plurality of lazy-tongs supporting the uprights, then there will be a plurality of pans 5 located one between each pair of lazy-tongs. Associated with each pan is a roller 22 which is mounted above the pan and at the rear end thereof, and disposed over this roller is a canvas or other flexible apron 23 10 which is adapted to be wound up upon the roller. The roller is preferably a spring roller, the spring being designated 24, which will act to withdraw the flexible apron. This apron passes over a roller 25 15 disposed at the forward end of the pan adjacent the front wall thereof, and this roller is designed to hold the apron up against a brush 26.

The forward end of the apron is connected 20 to irons 27 attached to and projecting from the forward end of the lazy-tongs or the apron may be attached directly to the lazy-tongs. On the other hand, and preferably, the apron will be provided with a member 28 which will latch into the irons 27, and a rope 29 is provided whereby the apron may be pulled out independently of the lazy-tongs, if desired. This canvas apron may be impregnated with kerosene, 30 gasoline or other liquid which will be inimical to mites or other vermin. It will be obvious now that when the roost is pulled out or expanded, the apron will also be drawn out even with the lazy-tongs or independently thereof and held in its expanded 35 position by any suitable means. When the apron is retracted by the spring roller 22, the brush 26 will sweep the droppings from the upper face of the apron into the pan.

40 In Figure 5, I illustrate a modified form of roost and a modified means of mounting the apron. The lazy-tongs is as before described, and is formed of the links 14 pivoted to each other at 15, carrying the roosts 45 16 and the uprights 17 just as before described, and these lazy-tongs are connected to the clips 12 also as previously described mounted upon the upright rod or bar 11. The sliding support 19, however, is omitted 50 and the last link 14^a of the lazy-tongs is extended downward beyond the other links of the lazy-tongs and carries a wheel 29 which bears upon the floor. Certain of the 55 links of the lazy-tongs are extended and at the intersection carry the rollers 30.

Disposed at the rear end of the hen house is the pan 31, and disposed slightly above this pan is the spring roller 32. Passing around this roller is the canvas apron 33 60 which rests upon the top of the supporting rollers 30 and at its free end is provided with hooks 34 to engage over the irons 35 which project from the members 14^a. Cords or ropes 36 are attached to these hooks so 65 that the canvas may be pulled out, or other

means might be provided for this purpose. Disposed above the pan and adjacent its forward end is a rotatable brush 37 which bears upon the upper surface of the apron 33, this brush being rotatable in a counter-clockwise direction and being rotated by the small belt 38. In this case, as the roost is forced inward, the canvas is retracted by the spring roller and this operates the rotary brush to sweep the droppings toward the forward edge of the pan, and as the brush passes entirely beneath the roller the droppings will be swept off of the apron into the pan.

As illustrated in Figure 6, the roosts or 80 perches 16 are supported inward of the lazy-tongs by inwardly extending brackets 39 and 40, the brackets 39 extending to the ends of the roosts and the brackets 40 extending toward intermediate pivots of the lazy-tongs 85 upward and inward to intermediate portions of the roosts or perches. Thus these roosts or perches are less in length than the canvas apron so that all droppings will be sure to drop upon the canvas apron and 90 not laterally outside of the same. Here again the canvas apron may be impregnated with kerosene, insecticide or other liquid if desired. It will be seen that these drop boards 95 formed by the canvas aprons not only provide means for collecting the droppings but keep the hen house clean and provide for a constant cleansing of these drop aprons, and also provide means whereby a relatively 100 large quantity of insecticide may be volatilized to impregnate the atmosphere.

In the use of this device, the lazy-tongs may be expanded by simply taking hold of the forward perch and pulling both sets of 105 lazy-tongs outward, or the lazy-tongs may be contracted by pushing inward upon the outermost perch. When the lazy-tongs is contracted, the greater portion of the hen house will be entirely unencumbered. At 110 night the roosts may occupy nearly the whole floor space, whereas when the lazy-tongs are compressed the roosts will only occupy about one-third or less of the floor space, thus making it easy to clean the floor of the 115 hen house and keep it in proper condition. Because of the fact that the perches have a strip soaked in kerosene or other insecticide, this roost is rendered very sanitary, as this strip will prevent mites 120 or other insects from climbing up the posts and onto the fowls and at the same time fowls coming in contact with the strip will become smeared, which will tend to keep the mites away.

I do not wish to be limited to the exact details which I have illustrated, as these might be modified in many ways without departing from the spirit of the invention as defined in the appended claims.

I claim:

1. A hen house having a plurality of parallel perches, a spring roller mounted in the rear of the hen house, a flexible apron mounted upon the spring roller and adapted to be pulled out to a position beneath the perches or wound up upon the spring roller, a catch pan disposed beneath the roller, and means for brushing the droppings from the apron into said pan.
  2. A hen house having a plurality of parallel perches, a drop pan disposed at the rear of the hen house and extending parallel to the perches and below the same, a spring roller mounted in connection with the pan, an apron of textile fabric mounted upon the roller and adapted to be wound thereon, means for holding the apron pulled out, and a brush mounted above the upper surface of the apron and acting to brush the droppings therefrom into the pan as the apron is retracted.
  3. A hen house having a plurality of lazy-tongs operatively supported adjacent one wall of the hen house and expansible toward the other wall of the hen house, uprights mounted upon the lazy-tongs and movable outward or inward with the expansion or contraction thereof, a pan mounted at the rear of the hen house and below the lazy-tongs, a spring roller mounted in connection with the pan, a fabric apron wound upon the spring roller, means whereby the apron may be connected to the forward ends of the lazy-tongs to thereby hold the apron extended, and means disposed above the apron and above the pan and adapted to clean the apron of droppings as the apron is retracted by the roller.
  4. A hen house having a plurality of lazy-tongs operatively supported adjacent one
- wall of the hen house and expansible toward the other wall of the hen house, uprights mounted upon the lazy-tongs and movable outward or inward with the expansion or contraction thereof, a pan mounted at the rear of the hen house and below the lazy-tongs, a spring roller mounted in connection with the pan, a fabric apron wound upon the spring roller, means whereby the apron may be connected to the forward ends of the lazy-tongs to thereby hold the apron extended, and means disposed above the apron and above the pan and adapted to clean the apron of droppings as the apron is retracted by the roller, the lazy-tongs having supporting rollers at intervals over which said apron passes.
5. In a hen house, a plurality of lazy-tongs mounted adjacent one wall of the hen house and expansible toward the other wall thereof, perches mounted upon said lazy-tongs and movable outward or inward with the expansion or contraction thereof, a pan disposed at the rear of the hen house beneath the rear portion of the lazy-tongs, a spring roller mounted above the pan at the rear thereof, an apron of flexible material wound upon the spring roller and having means at its forward end whereby it may be detachably engaged with the forward ends of the lazy-tongs, and a rotatable brush mounted above the forward end of the pan and above the apron, and a belt connection between the spring roller and said brush acting to rotate the brush in a direction to sweep droppings from the upper surface of the apron into the pan as the apron is contracted.

In testimony whereof I hereunto affix my signature.

JOHN C. WOBERMIN.
